UNITED STATES PATENT OFFICE.

CHARLES HENRY PALMER AND JOHN W. DENMEAD, OF AKRON, OHIO, AS
SIGNORS TO THE DIAMOND MATCH COMPANY, OF CHICAGO, ILLINOIS, A
CORPORATION OF ILLINOIS.

BOX-SANDING MACHINE.

SPECIFICATION forming part of Letters Patent No. 709,033, dated September 16, 1902.

Application filed January 9, 1900. Serial No. 882. (No model.)

To all whom it may concern:

Be it known that we, CHARLES HENRY PALMER and JOHN W. DENMEAD, of Akron, in the county of Summit, and in the State of Ohio, have invented certain new and useful Improvements in Box-Sanding Machines; and we do hereby declare that the following is a full, clear, and exact description thereof, reference being had to the accompanying drawings, in which—

Figure 1 is a perspective view of a box-sanding machine embodying our invention. Fig. 2 is a top plan view thereof. Fig. 3 is a vertical longitudinal section of said machine. Fig. 4 is a section on the line $\alpha\alpha$ of Fig. 2. Fig. 5 is a detail perspective view of the reciprocating slide-carrying bar.

Letters of like name and kind refer to like parts in the several figures.

The object of our invention is to provide a machine for forming the scratch-surfaces of match-boxes which will be capable of doing satisfactory work and doing it very rapidly; and to this end said invention consists in the sanding - machine substantially as herein-after specified.

Our machine has been designed to apply sand to the exterior surface of match-boxes of the class consisting of a tray or receptacle part and a cover part in the form of a flat-sided tube, the cover part being commonly called the "shuck" or "slide," and the sand being applied to it.

Briefly set forth, the machine comprises a source of supply of shucks or slides to be sanded in the form of a trough or guide, a rapidly-reciprocating bar upon whose end the slides one at a time are taken, and a sanding mechanism comprising a glue-applying device past which the slides are moved by the bar, and a sanding device to and past which the slides are moved after receiving the glue.

In the embodiment of the invention shown in the drawings the various parts of the machine are mounted upon a table or bed A, supported by suitable legs a and a . Above the table A upon proper supports is a horizontal trough or guide B, that is open from end to end and at the top, and close to the bottom of

which for a portion of its length runs a band b , that passes over a pulley b' at one end of the trough and another, b'' , between the ends of the trough, power being applied to the latter pulley to drive said band. At one side of and parallel with said trough is a horizontal bar C, that is attached at one end to a sliding head c , mounted on horizontal guides D and D, bolted to standards E and E on the table A. The head c is reciprocated by means of a crank-disk F, to the wrist-pin of which it is connected by a pitman G, said disk being on a shaft H, having a driving wheel or pulley I. The free end of the bar C travels in a path that extends from a point a short distance in rear of the adjacent end of the trough B to a point some distance beyond such end. The shape of the free end of the bar C in cross-section is rectangular, and its size is such that it will fit within the slide to be sanded. Each slide as it emerges from the trough B is in the path of a carrier that reciprocates at a right angle to the trough and moves the slide into the path of the bar C, whose end passes into the slide as the bar moves forward, its end being beveled to enable it to readily enter the slide. Said carrier consists of a horizontal bar K, movable in suitable supports and having on its upper side a vertical projection L, which engages the side of the slide as it comes from the trough B. A cam M, engaging a stud k on the bottom of the bar K, and a spring N, connected at one end to the latter and at the other to a relatively fixed point and acting in opposition to the cam, produce the reciprocation of the bar K. The cam is on a shaft O, having a sprocket-wheel P, by which it is connected by a sprocket-chain Q to a sprocket-wheel S on the shaft H. To prevent the slide being moved too far on emerging from the trough B, a stop k' on the bar K comes opposite the open end of the trough, while to prevent the slide being moved beyond a position in alignment with the bar C a stop J is used. Exit of slides from the trough B while the slide-carrier is moving across its end is prevented by means of a second vertical projection L' on the slide-carrier, which closes such end of the trough dur-

ing the movement of the carrier. On one side of the bar C are shoulders or lugs c and c, which engage the inner end of the slide when the bar enters the latter, and the slide 5 is thereby carried along with the bar. In its movement with the bar C the slide is carried over a glue-applying mechanism U, of usual construction, comprising a pan or vat and a wheel that takes glue from the vat and applies it to the slide, and from said glue-applying mechanism the slide is carried by the further movement of the bar C into a trough or guide V, having top and sides, but no bottom. In its described travel with the bar C 15 the slide passes beneath a spring-plate W, fastened at one end to the top of said trough V, and any deformation of the slide which may exist at such time is removed by the pressure of the spring. Having placed the slide 20 in the trough V, the return movement of the bar C takes place, and for removing the slide from it there is a stripping device in the form of a spring X, attached to and projecting from the trough, with its free end hooked to catch 25 over the rear end of the slide and hold the latter from rearward movement with the bar C. The slides are moved through the trough V by those in the rear engaging and pushing the ones in advance, and in such movement 30 they pass over a sanding device Y, of usual construction, comprising a rapidly-revolving wheel that takes sand from a receptacle and throws it against the glue previously applied to the under side of the slides. The interior 35 dimensions of the trough V are such that the natural outward spring of the sides of the slides presses with sufficient friction on the trough-walls to prevent the slides dropping out of the trough. The trough V ends a 40 short distance beyond the point where the sand is applied to the slides, and the latter passing from the trough fall from the machine. The glue-wheel shaft Z has a band wheel or pulley A' for a driving-belt, and 45 from said shaft a train of gears transmits power to the sand-wheel, and also on said shaft Z is a pulley B', that is connected by a belt C' with a pulley D' upon the shaft carrying the band-wheel b², power being thus 50 transmitted to the latter to drive the slide-feeding band b.

The operation of the machine is as follows: Slides are placed by hand in that portion of the trough B through which the band b runs, 55 and resting on the latter they are carried end to end through the trough, those in that portion not traversed by the band being pushed onward by those that are. The end one of the row of slides emerging from the trough 60 is by the stop k arrested in the path of the projection L of the carrier-bar K and by the movement of the latter is carried into the path of the bar C, which is rapidly reciprocated. Stopped in the path of said bar by the lug or 65 flange T, the bar in its forward travel enters the slide, its shoulders c and c engaging the adjacent end thereof, and the slide is then

carried over the glue-wheel and beneath the spring W and then into the trough V, being stripped from the bar C as the latter moves 70 rearward. Pressed onward through the trough V by the succeeding slides, the one in advance is carried over the sanding-wheel and finally makes its exit from the trough V perfectly sanded and in perfect form. As 75 the construction of the machine permits the slide-carrying bar C to be reciprocated at high speed, the rapidity with which the machine can sand slides is practically limited only by the rate at which slides are fed into the receiving-trough B.

Having thus described our invention, what we claim is—

1. In a sanding-machine, the combination of sanding mechanism, a reciprocating bar 85 by which box parts are conveyed to the latter, and means for feeding box parts in a path crosswise of said bar, in position for the end of the latter to enter therein, substantially as and for the purpose described. 90

2. In a sanding-machine, the combination of sanding mechanism, and a reciprocating bar adapted to enter and engage a box part and carry it to the sanding mechanism, substantially as and for the purpose described. 95

3. In a sanding-machine, the combination of sanding mechanism, a reciprocating bar adapted to enter and engage a box part and carry it to the sanding mechanism, and means for feeding box parts into the path of the bar, substantially as and for the purpose described. 100

4. In a sanding-machine, the combination of sanding mechanism, a reciprocating bar adapted to enter and engage a box part and 105 carry it to the sanding mechanism, a source of supply of box parts, and means for feeding them from said source of supply into the path of the bar, substantially as and for the purpose described. 110

5. In a sanding-machine, the combination of sanding mechanism, a box-part carrier for conveying box parts to the latter, a box-part guide alongside the path of said carrier, and means for passing box parts from the guide 115 to the carrier, substantially as and for the purpose described.

6. In a sanding-machine, the combination of sanding mechanism, a reciprocating bar adapted to receive and convey box parts to 120 said mechanism, a box-part guide alongside the path of the bar, and means for passing box parts from the guide into the path of the carrier, substantially as and for the purpose described. 125

7. In a sanding-machine, the combination of sanding mechanism, a reciprocating bar adapted to receive and convey box parts to said mechanism, a trough-form, box-part guide alongside the path of said bar, and means for passing box parts from the guide into the path of the bar, substantially as and for the purpose described. 130

8. In a sanding-machine, the combination

of sanding mechanism, a reciprocating bar adapted to receive and convey box parts to said mechanism, a trough-form, box-part guide alongside the path of said bar, and a box-part carrier that is movable crosswise of said guide, substantially as and for the purpose described.

9. In a sanding-machine, the combination of sanding mechanism, a reciprocating bar adapted to receive and convey box parts to said mechanism, a trough-form, box-part guide alongside the path of said bar, a conveyer at the bottom of the guide, and means for passing box parts from the guide into the path of the bar, substantially as and for the purpose described.

10. In a sanding-machine, the combination of sanding mechanism, a reciprocating bar adapted to receive and convey box parts to said mechanism, and a yielding device adjacent to the path of the bar and adapted to engage a box part carried thereby, substantially as and for the purpose described.

11. In a sanding-machine, the combination of sanding mechanism, a reciprocating box-part-carrier bar, a trough with an open bottom, in line with said bar, and a spring adjacent to the path of the bar in position to en-

gage a box part thereon, substantially as and for the purpose described. 30

12. In a sanding-machine, the combination of sanding mechanism, a box-part carrier, a box-part guide, and a second box-part carrier movable between the guide and the first carrier, substantially as and for the purpose described. 35

13. In a sanding-machine, the combination of sanding mechanism, a box-part-carrying bar, means for reciprocating the same, a trough-form box-part guide parallel with the path of said bar, a box-part carrier movable in a path that is crosswise of that of the bar, a trough-form guide into which the bar moves the box part, a spring to press against the box part when on the bar, and a device to remove the box part from said bar, substantially as and for the purpose described. 40 45

In testimony that we claim the foregoing we have hereunto set our hands this 6th day of November, 1899.
